ULTRAHIGH FREQUENCY OSCILLATOR
SYSTEM

Klaas Posthumus, Eindhoven, Netherlands, assignee to Radio Corporation of America, a corporation of Delaware

Application August 25, 1934, Serial No. 741,393
In the Netherlands September 6, 1933

5 Claims. (Cl. 250—17)

This invention relates to an arrangement for producing high frequency and ultrahigh frequency electric oscillations and more particularly to a thermionic generator in which the 5 circuit determining the frequency lies between two or more electrodes of a discharge tube. As an example of such a generator, we may mention a magnetron-oscillator comprising two or more anodes which are symmetrically arranged with 10 respect to an incandescent cathode and in which an oscillatory circuit determining the frequency of the produced oscillations is provided between the anodes. Oscillations are produced in this circuit since a negative resistance is inserted between the electrodes. However, it is necessary, 15 in this case, that the resistance of the circuit substantially corresponds to the negative resistance between the electrodes. In many cases it will be desirable, however, that the resistance of 20 the circuit be accommodated to the internal resistance. More particularly, when the frequency-determining circuit of a magnetron-oscillator is constituted by an antenna-dipole, accommodation will be necessary, since the resistance of 25 such an antenna is low and the negative resistance of a magnetron-oscillator is high.

According to the invention, the desired accommodation is ensured by connecting the frequency determining circuit to the electrode terminals through conductors, having such a length 30 that the electric distance between the electrodes and the oscillatory circuit amounts to one-quarter wave length of the oscillations to be produced.

Preferably, the frequency-determining circuit 35 is connected to the conductors through condensers having such a size that the influence exerted by the interelectrode capacity on the total external impedance is compensated.

The invention will be more clearly understood 40 by reference to the accompanying drawing which represents only the parts required for a good understanding of the working of the arrangement.

In this drawing, 2 and 4 denote a sectional view 45 of the anodes of a magnetron oscillator. The cathode of this oscillator, which is perpendicular to the plane of the drawing, is denoted by K. A field winding 26 may be used for the generation of oscillations. The source of anode-voltage is connected to the anodes 2 and 4 over 50 conductors 24, the length of each of which amounts to one-quarter wave length of the oscillations to be reproduced. That is to say, each of the conductors 24 together with a portion of

the bridging conductor 25 to the midpoint thereof, has substantially a quarter wave length so that a nodal point is formed at the midpoint of the bridging conductor 25. The oscillation circuit of the generator is constituted by both parts 5 of a dipole antenna 6. One arm of this antenna is connected through the condenser 16 and the conductors 8 and 20 to the electrode terminal 2. The other antenna arm is connected through the condenser 18 and conductors 10 and 22 to the 10 electrode terminal 4.

According to the invention, the conductors 8 and 10 have such a size that, together with the electrode supply wires 20 and 22, they have a 15 length of one-quarter wave length of the oscillations produced by the generator. They thus achieve the required accommodation or matching of the impedance of the oscillatory circuit; in the case under review the accommodation of the impedance of antenna 6 to the negative resistance between the electrodes 2 and 4. In fact, 20 it will be appreciated that if the impedance at the end of a line having a length of one-quarter wave length be z , the impedance at the beginning of this line may be represented by 25

$$\frac{R^2}{z}$$

where R is the wave resistance of the line. By 30 using this realization, which is known per se for accommodating the output impedance of an oscillator to the internal resistance of this oscillator, an arrangement is obtained in which the influence of the interelectrode capacity, which lies 35 in parallel with the resistance between the electrodes, viz. the resistance

$$\frac{R^2}{z}$$

40

can be compensated.

According to the invention, the condensers 16 and 18 are provided for this purpose. Assuming the impedance of said condensers to be $-jx$ then, 45 if the impedance of the antenna be z , as we assumed already before, the impedance between the electrodes 2 and 4 corresponds to

$$\frac{R^2}{z-jx}$$

50

In this case the admittance is

$$\frac{z-jx}{R^2}$$

55

In this case the total admittance between the electrodes 2 and 4 amounts to

$$\frac{z-jx}{R^2} \times jy$$

5 where jy is the admittance of the interelectrode capacity. When the condensers 16 and 18 are now given such a size that

$$10 \quad \frac{x}{R^2} = y$$

the impedance between the electrodes 2 and 4 will be

$$15 \quad \frac{R^2}{z}$$

and the interelectrode capacity is compensated.

What is claimed is:

1. A thermionic generator for producing high frequency and ultra-high frequency oscillations comprising an electron discharge tube having a pair of anodes symmetrically disposed about a cathode, an oscillatory circuit including two arms of a dipole antenna system, means including a pair of parallel conductors, each in series with a capacitor, interconnecting each anode respectively with one of said antenna arms for producing an impedance match between the portions of said circuit that lie within and outside of said tube respectively, and means including a source of direct current potential and circuit connections in series therewith interposed between said cathode and said anodes for supplying said discharge tube with the required polarization of its electrodes.

2. A generator in accordance with claim 1 and having a conductive bridge-circuit included in the electrode polarization means, the electrical

length of each half of said bridge-circuit being substantially equal to a quarter-wave length of the oscillations generated.

3. A generator in accordance with claim 1 and having said capacitors so disposed in circuit with said impedance matching means that the interelectrode capacity is effectively compensated.

4. An electronic generator for producing high frequency and ultra-high frequency oscillations comprising an electron discharge tube having at least one pair of anodes symmetrically disposed about a cathode, an oscillatory circuit including two capacitors so dimensioned that the interelectrode capacity of the discharge tube is effectively compensated, two arms of a dipole antenna system each arm being coupled to said oscillatory circuit through one of said capacitors, respectively, and a pair of impedance matching conductors, each conductor extending between one of said anodes and one of said capacitors respectively and having an electrical length substantially equal to a quarter wave length of the waves generated, and means including a source of direct current potential and circuit connections in series therewith interposed between said cathode and the anode connected terminals of the discharge tube for supplying to said discharge tube the required polarization of its electrodes.

5. A generator in accordance with claim 4 and having a conductive bridge-circuit included in the electrode polarization means, the electrical length of said bridge-circuit being substantially equal to a half-wave length of the waves generated.

KLAAS POSTHUMUS.
